UNITED STATES PATENT OFFICE.

JULES HALTENBERGER, OF INDIANAPOLIS, INDIANA.

INTERNAL-COMBUSTION ENGINE.

1,090,147.

Specification of Letters Patent. Patented Mar. 17, 1914.

Application filed September 27, 1911. Serial No. 651,578.

To all whom it may concern:

Be it known that I, JULES HALTENBERGER, a citizen of Austria-Hungary, residing at Indianapolis, in the county of Marion and State of Indiana, have invented a new and useful Internal-Combustion Engine, of which the following is a specification.

It is the object of my invention to improve the construction of internal combustion engines of the sliding valve type and particularly of the sleeve type.

By my invention a valve or valve sleeve is given an absolutely smooth motion having both axial and rotary components and is operated by a single train of mechanism from the crank shaft. Any point on the sleeve moves in a smooth closed curve.

The various novel features of my invention will appear from the description and drawings and will be pointed out in the claims.

In the drawings, Figure 1 is a longitudinal section, substantially on line 1—1 of Fig. 2 through a single sleeve gas engine embodying a preferred form of my invention; Fig. 2 is a section through the sleeve, substantially on line 2—2 of Fig. 1; and Fig. 3 is a view similar to Fig. 2 but showing the application of my invention to a double sleeve engine.

In the preferred form of my invention, the piston 10 moves longitudinally in the sleeve or inner cylinder 11, and said sleeve is mounted in and movable both axially and 35 rotatively relatively to an outer cylinder or frame 12. This location of the sleeve 11, however, is not essential. The outer cylinder 12, which may be jacketed to provide spaces 13 for the circulation of a cooling 40 fluid, is fixed to the top of a crank case 14 in which is mounted a crank shaft 15 connected to the piston 10 by a pitman 16. A counter shaft 17 is also mounted in the crank case 14 near the top thereof and to 45 one side, and, in the four-cycle engine shown, this counter shaft 17 is connected to the crank shaft 15 by a two-to-one reduction gearing 18, 19. The desired closed curve movement of the sleeve 11 is obtained 50 from this counter shaft 17. This movement may be obtained by an arm 20 which is located between two flanges 21 and 22 on the lower end of the sleeve 11 and is pivotally connected at one end to said flanges by a pin 55 23 parallel to the axis of the sleeve 11. The

other end of the arm 20 is mounted on an eccentric device, such as a crank or eccentric 60 24, on the counter shaft 17, the mounting being such that a slight side play of the arm 20 is permitted. The sleeve 11 is provided with one or more inlet ports 25 and one or more exhaust ports 26, which co-operate, respectively, with inlet and exhaust 65 openings 27 and 28 in the outer cylinder 12.

In the operation of the engine, the counter 70 shaft 17 makes one revolution for each two revolutions of the crank shaft 15. By the rotation of the counter shaft 17, and the connection between it and the sleeve 11, the latter is moved both axially and circumferentially, any particular point on the sleeve 75 describing a closed curve. Because of the long bearing of the arm 20 on the flanges 21 and 22, the sleeve 11 is moved vertically or axially a distance equal to the vertical component of the movement caused by the eccentric 80 24, the arm 20 being maintained always longitudinal. This vertical component is always associated with an equal horizontal component, which moves the pin 23 the same distance about the axis of the sleeve as a center, thus turning the sleeve on its axis. The resultant of these two components produces a simultaneous axial and rotary movement of the sleeve 11, which movement is a 85 smooth closed curve. In the four-cycle engine illustrated, the ports 25 and 26 are so located relatively to each other and to the inlet and exhaust openings 27 and 28 that the exhaust port is opened, or made to register 90 with the exhaust opening 28, at every second up-stroke of the piston, and the inlet ports 25 are opened, or made to register with the inlet openings 27, on the down strokes of the piston which immediately follow the aforesaid up-strokes, the ports being closed during the remaining up and down strokes, or during compression and explosion. It is not essential, and indeed it is 95 usually not desirable, that the inlet and exhaust ports open and close precisely at the beginning and end of the intake and exhaust strokes; this may be varied in accordance with conditions.

The same general arrangement may be 100 applied in double sleeve engines, as shown in Fig. 3. Here there are two coaxial sleeves 11^a and 11^b, having co-operating inlet ports 25^a and 25^b and co-operating outlet ports 26^a and 26^b. The two sleeves are operated, in 110

opposite directions, from eccentric devices 24^a and 24^b on counter shaft 17 in the same manner as is the single sleeve 11 in the modification shown in Figs. 1 and 2.

5 My invention is capable of considerable modification from the preferred embodiment illustrated, and I aim to cover all modifications which do not involve a departure from the spirit and scope of my invention as set forth in the following claims.

10 What I claim as new is:

1. In an internal combustion engine, the combination of a cylinder, a casing sleeve movable both axially and rotatively and provided with ports controlled by such movement, a piston movable in said cylinder, a crank shaft operated by said piston, a counter shaft connected to said crank shaft so as to operate at one-half the speed thereof, an eccentric device on said counter shaft, a connecting rod transverse to the countershaft and operated by said eccentric device and pivoted to said sleeve, and means for maintaining the connecting rod parallel to a plane transverse to the plane in which the eccentric device moves.

2. In an internal combustion engine, the combination of a cylinder movable both axially and rotatively and provided with ports which are controlled by such movement, a piston movable in said cylinder, a crank shaft to which said piston is connected, a counter shaft geared to said crank shaft by a two-to-one reduction gearing, an eccentric device on said counter shaft, and a connecting rod transverse to the counter-shaft and operated by said eccentric device and pivoted to said cylinder on an axis substantially at right angles to said counter shaft.

3. In an internal combustion engine, the combination of a cylinder movable both axially and rotatively and provided with ports which are controlled by such movement, a piston movable in said cylinder, a crank shaft to which said piston is connected, a counter shaft geared to said crank shaft, an eccentric device on said counter shaft, and a connecting rod transverse to the counter-shaft and operated by said eccentric device and pivoted to said cylinder on an axis substantially at right angles to said counter shaft.

4. In an internal combustion engine, the combination with the piston, of an eccentric device operated from the piston, a sliding valve, and a connecting rod between a movable part of the valve and the eccentric device for moving the former in a closed curved path always in the same direction, said connecting rod being transverse to the

axis on which the eccentric device turns and at all times being parallel to a given plane.

5. In an internal combustion engine, the combination with the piston, of an eccentric device 65 operated from the piston, a sliding valve, and a connecting rod of constant length between a movable part of the valve and the eccentric device for moving the former in a closed curved path, said connecting rod always being parallel to a given plane.

6. In an internal combustion engine, the combination with the cylinder and piston, of a valve sleeve for said engine, an eccentric device operated from said piston, a pair of parallel plane flanges on said valve sleeve, and a connecting rod fitting between said flanges and pivoted thereto to swing in a plane parallel thereto, said connecting rod 80 being mounted on said eccentric device.

7. In an internal combustion engine, the combination with the cylinder and piston, of a valve sleeve for said engine, an eccentric device operated from said piston, and a connecting rod between said eccentric device and said valve sleeve for moving the latter in a closed curved path, said connecting rod being attached to said sleeve and said eccentric device so that it has a reciprocating 90 swinging movement relative to both and is always parallel to a given plane.

8. In an internal combustion engine, the combination with the cylinder and piston, of a valve sleeve for said engine, an eccentric device operated from said piston, and connecting means between said eccentric device and said valve sleeve for moving the latter in a curved path having components both axially and circumferentially of the 100 sleeve, said connecting means being rigid and at all times parallel to a given plane.

9. In an internal combustion engine, the combination with the cylinder and piston, of a valve sleeve for said engine, a counter-shaft operated from said piston, the axis of said countershaft and the axis of said sleeve being non-intersecting, an eccentric device mounted on said countershaft, and a connecting rod pivoted to said valve sleeve 110 and having a universal mounting on said eccentric device, said connecting rod extending transversely to the countershaft.

In witness whereof, I have hereunto set my hand and seal at Indianapolis, Indiana, 115 this 21st day of September, A. D. one thousand nine hundred and eleven.

JULES HALTENBERGER. [L. S.]
